UNITED STATES PATENT OFFICE.

WILLIAM F. HUDSON, OF PHILADELPHIA, PENNSYLVANIA.

COVER FOR AUTOMOBILE RUNNING-BOARDS.

1,178,723.

Specification of Letters Patent. Patented Apr. 11, 1916.

Application filed January 19, 1915. Serial No. 3,086.

To all whom it may concern:

Be it known that I, WILLIAM F. HUDSON, a citizen of the United States, residing at Philadelphia, in the county of Philadelphia and State of Pennsylvania, have invented a certain new and useful Improved Cover for Automobile Running-Boards, of which the following is a specification.

This invention broadly stated relates to automobile running boards of sheet steel and the like and has more particular relation to the providing of auxiliary covers therefor.

Sheet metal and like running boards of automobiles are somewhat unsatisfactory for the reason that they are painted or shellacked and very soon show the signs of wear and gradually become rusty, thus necessitating the expense and inconvenience of having the same done up or else permitting same to remain in a condition detrimental to the appearance of the machine.

The object of the present invention is to overcome this disadvantageous feature and provide an auxiliary cover of non-corrosive material, preferably aluminum, which is light, strong, durable and inexpensive to manufacture and which may be readily applied to the ordinary metal running board of an automobile without the employment of tools, for preserving the running board against wear and tear and for maintaining a good appearance running board at all times.

The invention consists of the improvements hereinafter described and finally claimed.

The nature, characteristic features and scope of the invention will be more fully understood from the following description taken in connection with the accompanying drawings, forming part hereof and in which:

Figure 1, is a view in perspective of the auxiliary cover of the invention in application to the running board of an automobile which latter is shown in dotted lines, Fig. 2, is a perspective view of the cover detached and illustrating the underside of the same, Fig. 3, is an end view of the cover, and Fig. 4, is an end view of a running board fitted with the cover of the invention.

In the drawings, 10, designates a metallic running board of an automobile, which running board is usually supported by the mud guards 11. The running board top is

slightly depressed as at 12, see Fig. 4, thus forming longitudinal, marginal ribs 13. The top is further provided with a series of protuberances 14, to provide strength and rigidity. Cross pieces 15, of wood are also present with which the running board has bolted relation as at 16. These parts are of well known construction and form no part of the present invention. Such a running board is painted or shellacked or otherwise treated as is well understood in the automobile trade. Because of the wear and tear to which the running board is subjected the paint soon wears off in spots, in fact after a few days' use, and besides being unsightly, corrosion takes place, thus further adding to its detrimental appearance. Thus the running board must be frequently re-painted to maintain the same in first class condition.

By the use of the cover of the present invention, this expense and inconvenience may be saved. In manufacture the auxiliary cover, which is designated 17, is constructed of aluminum, in one piece and comprises a channeled, elongated structure of a length and width to readily fit over the running board 10. The top of the cover is flat as 18, in contradistinction from being depressed as is the running board 10. The side walls 19, of the cover, terminate in inwardly and upwardly bent portions to form longitudinal grooves 20, see Fig. 3, so that the side walls of the running board may be engaged within said grooves and the cover readily slipped over the running board. This position is best illustrated in Fig. 4, and in this connection it is to be noted that the cover top rests upon the ribs 13, protuberances 14, and the heads of the bolts 16. The side walls 19, at one end of each cover are chamfered off as at 21, to make a neat fit with the front mud guards. The cover top is provided with a multiplicity of protuberances 22, to provide strength and rigidity and to present a good appearance.

In practice, to equip a running board with a cover as above described, it is merely necessary to remove the former from the mud guards, slip the cover over the running board and re-attach the same, in which position it will be observed the cover is interlocked against removal and all securing bolts are hidden from view by the cover. The above described cover is light and durable in structure, is cheap to manufacture and being of non-corrosive metal maintains a

good appearance at all times, and not requiring paint does not readily show signs of wear.

What I claim is:

- 5 1. As a complete article of manufacture, a slip-on cover designed for free sliding engagement over a flanged automobile running board embracing an elongated one-piece channeled member of rigid material
- 10 having a flat top indented to provide strength and rigidity, the side walls of said member terminating in inwardly and upwardly extending portions forming continuous grooves for the accommodation of the flanges of a running board, said cover side walls being chamfered off at one cover end.
- 15 2. In combination an automobile including its complemental mud guards and flanged running board bolted thereto of an auxiliary slip-on cover designed for free sliding engagement over said running board

when detached for completely covering the top and flanges of said running board including the heads of said bolts, said cover embracing an elongated one-piece channeled member of rigid material, the side walls of which terminate in inwardly and upwardly extended portions to form continuous grooves for coöperatively engaging over the flanges of the running board so as to be interlocked with respect thereto when the running board is bolted to position upon the automobile, said cover side walls being chamfered off at one cover end to fit with a mud guard. 35

In testimony whereof, I have hereunto signed my name in the presence of two witnesses.

WILLIAM F. HÜDSON.
